GILBERT D. JONES, OF NEW YORK, N. Y.

Letters Patent No. 65,752, dated June 11, 1867.

IMPROVEMENT IN PRESSES.

The Schedule referred to in these Letters Patent and making part of the same.

TO ALL WHOM IT MAY CONCERN:

Be it known that I, GILBERT D. JONES, of the city, county, and State of New York, have invented certain new and useful Improvements in Presses; and I do hereby declare that the following, taken in connection with the drawings, is a full, clear, and exact description thereof. In the drawings—

Figure 1 is a front elevation of the press.

Figure 2 is an end elevation thereof; and

Figure 3 is a longitudinal vertical section through the press.

These improvements are chiefly applicable to hay-presses, but are useful in other species of presses, and are shown in the drawings as applied to a press with two followers moving towards each other, but some of my improvements may be used in presses with a stationary platform. These improvements consist, first, in a certain combination of toggles with the moving jaw, follower, or platen of a press; second, in the combination with such toggles of cogged sectors for operating them in unison; and third, in the combination with cogged sectors and toggles of a screw for operating a set of toggles; and lastly, in the combination of two sets of toggles with right and left-hand screws mounted upon the same shaft, whereby all the toggles are operated simultaneously without end play of the shaft.

In the drawings, the framing of the press is represented at *a a a*, the enclosure for the hay, cotton, &c., at *b b*, the door for discharging the compressed bale at *c*, and doors for the insertion of matter to be compressed at *d d*, the latter being held in place, when shut, by a latch, *e*. The two followers of the press are represented at *f f*, and to each follower are fastened, by proper pivots, the ends of the arms of three toggles *g h i*, *g' h' i'*, *g'' h'' i''*. One of these pivots is at the middle of the upper edge of each follower, or nearly so; the other pivots are at opposite extremities of the lower edge of each follower, or nearly so. The three pivots occupy the angles of an isosceles triangle, whose base is near to and parallel with the lower edge of each follower, and the gist of this arrangement of pivots is, that they occupy the angles of an isosceles or equilateral triangle, or nearly so, thus forcing the follower to move parallel to itself, or nearly so, when the toggles are moved simultaneously at the same velocity, thus rendering guides for the follower almost unnecessary, and obviating the great friction usually generated by the follower moving on the guides, when the resistance to such follower is as it usually is, unevenly distributed over its surface. To each of the three arms are pivoted other arms, *k l m*, *k' l' m'*, which are also pivoted to some stationary part of the framework. Various mechanical contrivances may be applied to cause each set of toggles to move simultaneously, but I prefer to make each of the arms furthest from the follower carry racks or cogged sectors *o p q r*. These sectors are all of the same diameter, and are located one on each side of the central arms *l l'*, and the others on the sides of the arms *k k'*, *m m'*, adjacent to the central arms *l l'*. The arrangement of these racks is clearly shown in the drawings, also their gearing together, and it is obvious that they so connect each three toggles in each set, that they must move simultaneously and at the same velocity, or in unison, when any one of the three is caused to move. I prefer to apply the power to the centre toggle of each set through some appropriate mechanical device, but the best way of applying it is by means of cogged sectors *s s*, which are attached to or make part of the outer arm of the centre toggle of each set, and I cause screws *t t* to gear into them, so that by the revolution of the screw-shaft the toggles of each set are operated. When two followers and two sets of toggles are employed, as in the form in which my invention is represented in the drawings, I intend to make one screw a right-hand and the other a left-hand one, and to mount them upon the same shaft; a revolution of the shaft will then cause the two followers to move at the same time in opposite directions, and there will be no strain upon the shaft to move it endwise. When a press is made with a stationary bed and but one moving follower, then but one set of toggles is to be employed, but the toggles of this set must be arranged relatively to each other, and be pivoted to the follower substantially at the points or in the relation to each other of the pivots set forth. I intend to apply the right and left-hand screws, and the sectors with which they gear, in combination with sets of toggles differing in their arrangement from those described, thus using one part of my invention separate from the others.

I claim as of my own invention—

1. In combination with the follower of a press, three toggles arranged relatively to each other and pivoted

to the follower in the relation to each other substantially as set forth, the combination being substantially as described, and operating substantially as set forth..

2. In combination with three toggles I claim cogged sectors attached and gearing together substantially as described, whereby the three toggles may be made to move in unison as set forth.

3. In combination with three toggles and their cogged sectors I claim a sector in gear with a screw, the combination being substantially as described and operating substantially as set forth.

4. In combination with two sets of toggles to operate followers in opposite directions, I claim right and left-hand screws mounted upon the same shaft, the combination being and acting substantially as set forth.

G. D. JONES.
